US00D594449S

(12) **United States Design Patent**
Wozniak

(10) **Patent No.:** **US D594,449 S**
(45) **Date of Patent:** **** Jun. 16, 2009**

(54) **SET OF KEYS FOR A HANDSET**

(75) Inventor: **Leonard Wozniak**, Santa Monica, CA
(US)

(73) Assignee: **Nokia Corporation**, Espoo (FI)

(**) Term: **14 Years**

(21) Appl. No.: **29/305,523**

(22) Filed: **Mar. 21, 2008**

(51) **LOC (9) Cl.** **14-03**

(52) **U.S. Cl.** **D14/247**

(58) **Field of Classification Search** **D14/137, D14/138 R, 138 AA, 138 AB, 138 AC, 138 AD, D14/138 C, 138 G, 147, 191, 203.1–203.8, D14/218, 247–248, 341–347, 432, 439, 455–456, D14/496; D10/65, 78, 104; D13/168; D18/7; 455/556.1, 566, 575.1, 575.3; 345/169**

(57) **CLAIM**

The ornamental design for a set of keys for a handset, as shown and described.

DESCRIPTION

FIG. 1 is a front perspective view of a set of keys for a handset showing my new design; and

FIG. 2 is a front view thereof.

FIG. 3 is a front perspective view of a keypad showing my new design;

FIG. 4 is a front view thereof;

FIG. 5 is a right side view thereof;

FIG. 6 is a left side view thereof;

FIG. 7 is a top view thereof;

FIG. 8 is a bottom view thereof; and,

FIG. 9 is a rear view thereof.

The broken line showing of the remainder of the handset is directed to environment and is for illustrative purposes only; the broken lines form no part of the claimed design.

1 Claim, 6 Drawing Sheets
